UNITED STATES PATENT OFFICE.

JOHN MILTON SPRECHER, OF EPHRATA, PENNSYLVANIA.

AIR-HEATING RADIATOR.

SPECIFICATION forming part of Letters Patent No. 609,595, dated August 23, 1898.

Application filed April 18, 1898. Serial No. 678,047. (No model.)

To all whom it may concern:

Be it known that I, JOHN MILTON SPRECHER, a citizen of the United States and a resident of Ephrata, in the county of Lancaster and State of Pennsylvania, have invented 5 certain new and useful Improvements in Air-Heating Radiators, of which the following is a specification.

My invention relates to radiators for heating 10 the air of a room by drawing it continuously through the drum and in contact with the walls thereof, which are kept hot by the waste heat passing off with the products of combustion from a fire.

15 My invention has for its objects to devise a heating-radiator which will be more effective for the purpose for which it is intended and which shall be of cheap and durable construction and made up of parts easily assembled 20 for use or taken apart for cleaning.

25 The principle employed for increasing the efficiency of my improved radiator is to so arrange the smoke and air chambers that the former shall surround the latter, whereby the 30 heat may be concentrated inward in the circulating air to be heated and radiated outward to the outer atmosphere of the room, the products of combustion being given the greatest opportunity to throw off their otherwise-wasted heat from the enlarged outer 35 chamber, while the column of circulating air is confined to a comparatively smaller section and is thus heated more fully and circulated more rapidly.

35 While not claiming novelty in this principle *per se*, my invention consists in the construction of the upper and lower heads of the drum, whereby the products of combustion 40 are received and discharged through axial openings arranged for convenient attachment of the smoke-pipe, and the air to be heated enters and discharges through a surrounding concentric series of ports, while the direction of the heating-gases and heated air, respectively, into the outer and inner concentric 45 chambers is effected by dividing the heads radially into compartments which are made to communicate alternately with the outer and inner chambers and to connect them with 50 ports leading, respectively, to the axially-connected smoke-pipes and the surrounding atmosphere.

A further feature of my invention resides in the choking or retarding effect produced by the peculiar formation of the heads, whereby the heating-gases and heated air are retained within the drum till the former gives up its heat. 55

A further feature consists in constructing the upper head so that the ports in the radial sections of the head may be opened or closed at will to regulate the heating effect of the drum. 60

My invention will be fully understood upon reference to the accompanying drawings, in 65 which—

70 Figures 1 and 2 are respectively an elevation and a vertical axial section of a heating-radiator embodying the main features of my invention. Figs. 3 and 4 are horizontal sections taken through Figs. 1 and 2, the one in a plane between the heads and the other in a plane through one of the heads. Figs. 5 and 6 are sectional detail views showing two constructions of the upper head. By the latter 75 the capacity of the drum may be regulated at will by graduating the air-outlet.

75 The drum comprises an outer cylindrical body 1, preferably fluted for the purpose of increasing its rigidity and heating-surface, an 80 inner concentric cylinder 2, also preferably fluted, a lower head 3, preferably provided with legs or other supports 4, and an upper head 5. The heads are provided with outer and inner flanges 6 and 7, which fit within 85 the respective cylinders to hold the parts in proper relative positions. The lower head is formed with two diaphragms 3^a and 3^b, forming, together with the outer wall of said head, a space which is utilized for flues in conducting the products of combustion or heating-gases and the air to be heated to the outer and inner chambers formed by the concentric cylinders 1 and 2. The upper head is made up of the lower diaphragm 5^b, which, together 90 with the outer wall, form a flue-space in the upper head. These flue-spaces in the respective heads are divided by radial partitions 8 into smoke-flues 9 and air-flues 10, of which the smoke-flues in the lower head receive the 95 products of combustion or heating-gases through inner segmental openings 11 in the lower diaphragm 3^a, said openings 11 communicating with a centrally-connected smoke- 100

pipe through the attaching flange 13 and discharge said smoke or heated gases through outer ports 11^a in the upper diaphragm 3^b into the outer or surrounding chamber 1. Alternating with the smoke-flues 9 are the air-flues 10, which receive cold air from the floor of the room through the outer ports 12 in the lower diaphragm 3^a and discharge the same into the central chamber 2 through the inner ports 12^a. At the top the heating-gases pass through the outer ports 11^{ax} in the lower diaphragm 5^b of the upper head and into the upper smoke-flues 9, whence they escape through the inner segmental ports 11^x to a centrally-connected smoke-pipe which is attached through the medium of the upper collar 13. The air to be heated arises from the central chamber 2 through the inner ports 12^{ax} of the lower diaphragm 5^b of the upper head into the upper air-flues 12^x, which alternate with the upper smoke-flues precisely as described with reference to the lower head, and the heated air escapes from the said air-flues 12 through the outer ports 12^x into the room to be heated.

From the foregoing description it will be seen that I have provided a cheap, effective, and durable structure which will take in and discharge the heating-gases through centrally-attached pipes and the air to be heated through ports near the outer edges of the drum, while the heating-gases pass upward through an outer or surrounding annular chamber, so as to heat the outer wall of the drum for radiation and the inner wall of the drum for transmitting heat to the air, while said air passes up through the central chamber, where the inwardly-radiated heating-gases will be concentrated in it, and it will be much more effectively heated, these results being accomplished by simply providing upper and lower heads formed with flue-spaces which are divided by radial partitions into flues, some of which are connected by ports in the inner diaphragms 3^b and 5^b with the smoke-chamber and other ports in the outer diaphragm 3^a and 5^a with attached smoke-pipes, while the other flues formed by the radial partitions are connected through ports in the inner diaphragms with the air-chamber and through ports in the outer diaphragms with the atmosphere of the room to be heated. To produce evenness of results, I prefer to alternate the flues, as has been described, although such is not of the essence of my invention.

A further object arising from the plan of construction of the heads is that such construction offers a basis for the arrangement of dampers to control the size of the ports of the air-chamber or at least to regulate the proportion of the air passing through the radiator which is delivered into the room, part being allowed to escape into the smoke-pipe or all being allowed to so escape, if desired for purposes of ventilation. This will be understood upon reference to Fig. 6, wherein 14

represents a rotary cap surmounting the upper diaphragm 5^a of the upper head carrying the smoke-pipe flange 13 and provided with 7^c air-ports 12^y, corresponding to the air-ports 12^x in the upper diaphragm, with which they are connected by inwardly-projecting flanges 15, which bear upon the upper diaphragm 5^a in such a manner as to space the rotary cap 75 from the diaphragm 5^a, so as to leave the smoke-chamber 16 under said cap, but at the same time to guard against the escape of smoke through the air-ports 12^y. With this construction it becomes an easy matter to rotate the cap 14, so as to bring more or less of the air-ports 12^y in the cap into coincidence with the air-ports 12^x of the upper diaphragm, and thus regulate the amount of hot air which is discharged through the ports 12^y. If the 80 ports 12^y are brought into complete coincidence with the ports 12^x, then the hot-air chamber discharges its full capacity of hot air into the room. Any movement of the cap 14 from this position, however, will result in discharging but a portion of the hot air into the room, while the remainder passes into the smoke-chamber 16 and off through the chimney or other place of outlet with which the drum may be connected. If the cap 14 is turned 95 sufficiently to cause the flanges 15 to rest upon a solid portion of the diaphragm 5^a, then all the hot air from the inner chamber 2 will pass into the smoke-chamber 16 and out with the heating-gases, and the result will be a ventilation of the room without discharging heated air into the room.

I find that in the use of my radiator or drum the gases take a spiral movement in passing through the radiator, thereby increasing its 105 heating capacity.

Having thus described my invention, the following is what I claim as new therein and desire to secure by Letters Patent:

1. A heating-radiator comprising inner and outer concentric chambers and upper and lower heads; each head made up of a side wall and inner and outer diaphragms and divided by radial partitions into flues; the inner diaphragms of each head being formed 110 with ports located to connect some of the flues with the inner concentric chamber, and the other flues to the outer chamber, and the outer diaphragms provided with ports located 115 for separately directing gases and air to and from the respective flues; substantially as explained.

2. In a radiator the combination of concentric walls forming inner and outer chambers; upper and lower heads, and centrally-located 125 smoke-pipe connections; said upper and lower heads being provided with inner diaphragms closing the ends of the concentric chambers, outer diaphragms for controlling inlet and discharge of air and smoke from the 130 flues, and radial partitions dividing the heads into flues; said inner diaphragms being provided with ports which connect the flues of the inner chamber with the outer atmosphere,

and the flues of the outer chamber with the respective smoke-pipe connections; substantially as explained.

3. A head for heating-drums, comprising 5 two diaphragms, a side wall and radially-arranged partitions dividing the space within the head into a number of segmental flues; said diaphragms being provided with ports communicating with the respective flues and located alternately at inner and outer ends of the flues and disposed so that each flue has an inlet and outlet at opposite ends and opposite sides; substantially as and for the purposes set forth.

5 4. In combination with a heating-drum head having radially-disposed flues arranged for communication with separate chambers of the drum and having separate discharge-openings at different radial distances from the center of the drum; a rotary cap 50 mounting said head and formed with a central pipe attachment communicating with the inner series of openings, and a series of outer openings corresponding to the outer series of 55 openings of the head and brought by rotation

of the cap into and out of coincidence with the openings of the head; substantially as and for the purposes set forth.

5. In combination with a heating-drum head having radially-disposed flues arranged 30 for communication with separate chambers of the drum and having separate discharge-openings at different radial distances from the center of the drum; a rotary cap 35 mounting said head and formed with a central pipe attachment communicating with the inner series of openings, and a series of outer openings corresponding to the outer series of openings of the head and brought by rotation of the cap into and out of coincidence with the openings of the head; said cap-openings having inwardly-projecting flanges which space the cap apart from the head and form a smoke-chamber; substantially as and for the purposes set forth.
